S. WALLWORK.
RAILWAY TIE AND SECURING DEVICE.
APPLICATION FILED APR. 18, 1922.

1,423,702.

Patented July 25, 1922.

UNITED STATES PATENT OFFICE.

SAMUEL WALLWORK, OF SUMMERVILLE, PENNSYLVANIA.

RAILWAY TIE AND SECURING DEVICE.

1,423,702.

Specification of Letters Patent. Patented July 25, 1922.

Application filed April 18, 1922. Serial No. 554,475.

To all whom it may concern:

Be it known that I, SAMUEL WALLWORK, a citizen of the United States, and a resident of Summerville, in the county of Jefferson 5 and State of Pennsylvania, have made a new and useful Invention in Railway Ties and Securing Devices, of which the following is a specification.

The invention relates to metallic railway 10 ties and more particularly to the fastening means for clamping the rails to the ties. It is designed for use in mine work but is not limited to use in such connection. It has for its principal objects; the provision of a tie 15 and securing device of cheap, simple construction in which the clamping means can be very easily applied and released or tightened in service, and in which the clamping effect is very secure and not liable to work 20 loose. Certain embodiments of the invention are illustrated in the accompanying drawings wherein;

Figure 1 is a plan view showing one form 25 of construction; Fig. 2 is an enlarged section on the line II—II of Fig. 1; Fig. 3 is a plan view illustrating a modification; Fig. 4 is a plan view of another modification involving the preferred form of construction; and Fig. 30 5 is a section on an enlarged scale on the line V—V of Fig. 4.

Referring to the construction shown in Fig. 1, the numeral 1 designates a metal tie 35 preferably in the form of a commercial channel with its flanges turned down and carrying at its ends the rails 2, 2 of the usual cross section. The flanges of the channel are cut adjacent the ends thereof, and such flanges and the web therebetween are turned up to form the hooks 3, 3 which fit around 40 the outer flanges of the rails and fix the gauge, and hold the rails against outward movement.

The inner sides of the rails are held by the clamping plates 4, 4, which are similar, 45 so the description will be directed to one only. The plate 4 is provided with a cam slot 5 which extends over a perforation in the tie (Fig. 2) and receives the clamping bolt 6. The upper end of the bolt carries 50 the nut 7, and to increase the bearing on the plate, the washer 8 is employed. The upper end of the bolt is preferably riveted over as indicated at 9 (Fig. 2) to maintain the nut in the position to which it is adjusted.

To apply the plate, the nut is adjusted so 55 that the inner edge of the plate or one cor-

ner thereof (which may be slightly thinned or bent up) just lies over the outer edge of the flange of the rail. The plate is then driven endwise in the direction of the arrow 60 by means of a sledge, the bolt, co-operating with the cam slot, camming the plate inward over the rail flange until sufficient overlap and a proper tension are secured in the plate. This will ordinarily occur before the 65 inner edge of the plate engages the web of the rail, and at this time the plate will be slightly bent as indicated in Fig. 2 so that a yielding spring tension is applied to the rail flange. This gives a very secure holding 70 of the rail even though the plate (which is ordinary steel plate) receives a partial set in the course of time. In case the grip of the plate loosens, it can be readily tightened by adjusting down the nut 7. 75

The procedure above set forth permits the clamping plates to be applied very quickly and securely, and when it becomes necessary to remove the plates, this is easily accomplished by driving the plates in the reverse 80 direction.

The slot 5 is preferably placed closer to the inner edge 10 of the clamping plate (Fig. 1) than to the outer side, so that when a larger rail is used the plate may still be 85 utilized by turning it end for end around the bolt 6, thus bringing the edge 10 over the flange of the rail.

Fig. 3 illustrates a modification in which the inner clamping plate 4 and its associate 90 parts are similar to those heretofore described in connection with Figs. 1 and 2, but the tie 11 is extended under the rail as indicated at 12, and a similar clamping plate 13 is applied on the outer side of the rail. 95 This plate is provided with a cam slot 14 and bolt 15 similar to the corresponding parts on the other side of the rail.

Fig. 4 illustrates a further modification in which the rail 2 is clamped by two plates 16 100 and 17 held by the single bolt 18. The plate 17 lies beneath the other plate and has its outer portion extended beneath the rail and provided with a hook portion 19 engaging the outer flange of the rail. The upper plate 105 16 is provided with a cam slot 20, and this plate and its co-operating bolt correspond throughout with the construction of Figs. 1 and 2, the bolt having a nut 21 and the plate being sprung as shown in driving it to position. The lower plate 17 has a slot 22 110 similar to the slot 20 but at the reverse angle

so that both plates may be driven in the same direction in order to tighten them by the same series of blows. In loosening, both plates are driven in the reverse direction.

5. It will be observed that the material used in all of the forms of construction consists of commercial sections and plates requiring little machine work and no special castings so that the construction can be very cheaply 10 fabricated. Also that the device is particularly adapted to mine work where much shifting and relaying of tracks and switches are required, since the clamps may be very easily and quickly applied by driving or 15 hammering the parts and with a minimum of labor in screwing and unscrewing of bolts such as is ordinarily required in track work. I have found that commercial plate as used 20 in the clamp has just the requisite amount of spring and give to lend itself to this method of procedure, and that the degree of security is ample for this class of work.

What I claim is;

1. The combination with a flanged rail 25 and a metal tie having a perforation adjacent the flange of the rail, of a clamping plate of wrought metal having a cam slot over said perforation and lying at an angle to the line of the rail with its edge lying 30 over the flange of the rail, and a headed locking member extending through said perforation and slot and clamping the plate so that the plate is sprung or bent and applies yielding pressure to the rail.

35. 2. The combination with a flanged rail and a metal tie having a perforation adjacent the flange of the rail, of a clamping plate of wrought metal having a cam slot over said perforation and lying at an angle 40 to the line of the rail with its edge lying over the flange of the rail, a screw-threaded locking member extending through said perforation and slot, and a nut on the said member above the plate and positioned so that 45 the plate is clamped against the rail flange with yielding pressure, the end of the member being riveted over to hold the nut in said position.

50. 3. The combination with a flanged rail and a metal tie having a perforation adjacent the flange of the rail, of a clamping plate

of wrought metal on the inside of the rail having a cam slot over said perforation and with its inner edge lying over the flange of the rail, a second clamping plate lying beneath the first clamping plate and also provided with a cam slot lying over said perforation and having its outer portion extended beneath the rail and provided with a hook at its outer end extending around the outer flange of the rail, and a headed locking member extending through said perforation and through the two cam slots. 55 60

4. The combination with a flanged rail and a metal tie having a perforation adjacent the flange of the rail, of a clamping plate of wrought metal on the inside of the rail having a cam slot over said perforation and with its inner edge lying over the flange of the rail, a second clamping plate lying beneath the first clamping plate and also provided with a cam slot lying over said perforation and having its outer portion extended beneath the rail and provided with a hook at its outer end extending around the outer flange of the rail, a threaded locking bolt extending through said perforation and the two cam slots, and a nut on the upper end of the bolt placing the inner clamping plate under clamping tension against the 75 flange of the rail. 80

5. The combination with a flanged rail and a metal tie having a perforation adjacent the flange of the rail, of a clamping plate of wrought metal on the inside of the rail having a cam slot over said perforation and with its inner edge lying over the flange of the rail, a second clamping plate lying beneath the first clamping plate and also provided with a cam slot lying over said perforation at an angle the reverse of that of the first clamping plate and having its outer portion extended beneath the rail and provided with a hook at its outer end and extending around the outer flange of the rail, 90 and a headed locking member extending through said perforation and through the two cam slots. 95

In testimony whereof, I have hereunto subscribed my name this 13th day of April, 100 1922.

SAMUEL WALLWORK.
